CLAIM

The ornamental design for a drinking glass, as shown and described.

DESCRIPTION

FIG. 1 is a perspective view of a drinking glass showing a first embodiment of my new design, the glass being generally transparent;

FIG. 2 is a front elevational view of the first embodiment; FIG. 3 is a top plan view of the first embodiment;

FIG. 4 is a bottom plan view of the first embodiment;

FIG. 5 is a perspective view of a drinking glass showing a second embodiment of my new design;

FIG. 6 is a perspective view of a drinking glass showing a third embodiment of my new design, the glass being opaque;

FIG. 7 is a front elevational view thereof;

FIG. 8 is a top plan view thereof;

FIG. 9 is a bottom plan view thereof; and,

FIG. 10 is a perspective view of a drinking glass showing a fourth embodiment of my new design.
